UNITED STATES PATENT OFFICE.

EMMET L. PETERSON, OF WILLACOOCHEE, GEORGIA.

COVERING FOR COTTON-GIN ROLLERS.

SPECIFICATION forming part of Letters Patent No. 615,103, dated November 29, 1898.

Application filed June 22, 1898. Serial No. 684,181. (No model.)

To all whom it may concern:

Be it known that I, EMMET L. PETERSON, a citizen of the United States, residing at Wil-
5 lacoochee, in the county of Coffee and State
of Georgia, have invented certain new and
useful Improvements in Coverings for Cot-
ton-Gin Rollers; and I do declare the follow-
ing to be a full, clear, and exact description
10 of the invention, such as will enable others
skilled in the art to which it appertains to
make and use the same, reference being had
to the accompanying drawings, and to the let-
ters of reference marked thereon, which form
15 a part of this specification.

15 This invention relates to certain new and
useful improvements in cotton-gin rollers,
and especially to a cover for the roller, whereby
the seed may be effectually separated from
20 the lint, doing the work in a less time and
leaving the lint in a better condition than by
the processes commonly in use.

More specifically the present invention re-
sides in the provision of a covering for the
25 roller, which is made up of alternate spirally-
arranged strips of leather and elastic mate-
rial, the leather strip provided with the in-
dispensable groove and serving as a firm body
30 upon which the blade and stripper play and
at the same time helping to despatch the lint
from the roller at the proper time, while the
elastic strip, with its adhesive qualities, forces
35 the cotton to the blade, making the work uni-
form and regular, which results in a better
cleansing of the lint and a greater amount of
work in a given time.

My invention will be clearly understood
when considered in connection with the draw-
ings which form a part of this application,
and in which—

40 Figure 1 is a perspective view of a cotton-
gin roller, showing about its circumference
my improved cover made up of alternate spi-
rally-arranged strips of leather and elastic
material. Fig. 2 is a central longitudinal sec-
45 tional view through the roller.

Reference now being had to the details of
the drawings by letter, A designates the roller
of the cotton-gin, which has spirally arranged
about its entire circumference in alternation
leather strips B and elastic strips C, the lat-
50 ter made of any suitable material which may
be found best adapted for the purpose, as of
rubber. The leather strip is grooved, as seen
at D, which grooved portion is provided to
allow the mote and trash to escape at the cut-
55 ing edge of the blade, the stripper ginning
it out with the seed. By providing the leather
strip arranged as shown and described it pre-
vents the stripper from tearing the elastic
strip when it becomes soft from steady run-
60 ning, as the said elastic strip becomes soft
when warm, and in which condition the leather
strip prevents the cotton from running around
the roller. Where a covering made entirely
65 of elastic material is employed, the covering
becomes ruffled by the blade and stripper and
causes the cotton to stick to it and run around
the roller and tear and break.

By my combining of the leather and elastic
strips in the manner described and illustrated,
70 the elastic strip takes the cotton in contact
with the leather and with the groove in the
leather strip, and it takes the staple quickly
through the gin without crimping or cutting
or breaking the staple, which renders the 75
product more valuable than the fiber pro-
duced by the processes commonly in use.

Having thus described my invention, what
I claim to be new, and desire to secure by Let-
ters Patent, is—

80 A gin-roller having a cover made up of al-
ternate strips of leather and elastic material,
the leather strip being grooved and the strips
arranged spirally about the roller, as set forth.

In testimony whereof I affix my signature 85
in presence of two witnesses.

EMMET L. PETERSON.
